CONNECTION FOR THE BITS OF SMOKING PIPES

Filed Sept. 30, 1949

FIG. 1

FIG. 2

FIG. 3

FIG. 4

INVENTOR.

Jerome Gevirmam
BY St. Lee Helms
attorney

Patented July 21, 1953

2,646,052

smoker's pipe having a bowl and bowl stem, a bit having a mouthpiece section at its end, and means for connecting the bit to the bowl stem.

The object of the present invention is to provide a smoker's pipe consisting of a bowl and bowl stem, a bit, and threaded connections intermediate the bit and the bowl stem enabling a tight fit between the said members and at the same time enabling the bit to be turned in a given direction, without changing the tight fit between the bit and the bowl stem, in order that the bit may be accurately positioned, with the flattened portion of the bit disposed at a right angle to the axis of the bowl.

The specific object of the invention is to provide a smoker's pipe of the stated character which possesses a predetermined frictional resistance between the bit and the bowl stem, which will maintain that condition, which will be capable of easy assembly, and which will be of low cost.

The invention will be described with reference to the accompanying drawings, in which:

Figure 1 is a top plan view of a smoker's pipe which may incorporate the invention, the bit having been adjusted to proper position and tight fit relatively to the bowl stem;

Figure 2 is a view similar to Fig. 1 showing the bit having been turned to a tight fit relatively to the bowl stem and yet out of proper position, requiring 90° rotation and to the position of Figure 1 for proper alignment.

Figure 3 is an enlarged fragmentary longitudinal section taken on the line 3-3, Figure 1;

Figure 4 is a composite enlarged view showing the bit and bowl stem connecting elements separated and in proper "line" position for assembly.

Referring to the drawings, I have shown at 1 the bowl of the smoker's pipe it having a bowl stem 2, the bit being indicated at 3.

Referring to Figure 3, it will be seen that the bowl stem is formed with a chamber 4, which receives the connector elements 5 and 6. The connector element or tube 5 is an externally threaded tube having a cylindrical portion, the latter having a smooth surface and a knurled head 7. The connector element 6 is a smooth-surfaced sleeve which is threaded on to the end of the connector element 5. It is preferred that the said sleeve be formed of a relatively firm material such as hard rubber or a plastic composition. It will have a smooth surface, and at the same time it will bear upon the wall of chamber 4 with a desired friction.

CONNECTION FOR THE BITS OF SMOKING PIPES

Jerome Gevirmian, Brooklyn, N. Y.

Application September 30, 1949, Serial No. 118,951

2 Claims. (Cl. 131—225)

2

The connector element 5 is apertured to form a small passageway, and the knurled head 7 is pressed into a chamber formed in the end of the bit. This chamber will have a diameter somewhat less than that of head 7. Preliminary to the assembly, the inner end of the bit is heated, as in hot water or oil, so that the material of the bit (which usually is of hard rubber) will yield and upon cooling the bit material will contract and firmly bond the knurled head thereto.

In practice the external thread on connector element 5 will be formed for clockwise rotation into the sleeve 6, until shoulder 7x of the connector element abuts the end of the sleeve. Therefore continued clockwise movement of the connector element 5 will compel rotation of the sleeve. The force required to effect such continued rotation of the sleeve will, of course, be substantially greater than that required in unthreading the connector element 5 from the sleeve. Therefore in disassembling the bit from the bowl stem, counterclockwise rotation of the bit will withdraw the connector element 5 from sleeve 6, the sleeve remaining in position within chamber 4.

A threaded member is employed to serve as a back-up for the sleeve. To that end I have provided an externally threaded member 8 having a flanged head 9. Thus when sleeve 6 has been pressed into chamber 4, member 8 may be threaded into that chamber, as shown in Fig. 3, until flange 9 is brought into abutment with the end of the bowl stem. At this point the bit, with the projected externally threaded and shouldered tube 5 will be brought into position and the tube threaded into the sleeve 6, preferably by clockwise rotation, until the point is reached at which relative rotation of sleeve 6 and tube 5 stops, and the tube and sleeve virtually become so interengaged as to provide, for all practical purposes, a single member which can be rotated by overcoming the frictional resistance between sleeve 6 and the wall of the chamber in the bowl stem indicated at 4.

It is not essential that tube 5 be threaded in friction sleeve 6.

The formation of annular shoulder 7x on the tube 5 has special utility in that it provides a stop or abutment between the tube and the friction sleeve 6.

The alignment between the bit and the bowl stem is effected according to this invention by inserting the knurled head 7 into the bit 3, next the threaded member 8 is pushed into place onto the smooth portion of connector element 5, then the rubber sleeve 6 screwed onto the threaded

portion of connector 5, and the assembled unit is inserted into the bowl stem and threaded element 8 is screwed into the bowl stem. To align the bit 3 with bowl stem 2, the bowl stem is grasped in one hand and the bit 3 is rotated with a sliding contact between sleeve 6 and bowl stem 2 and also a sliding contact between the smooth portion of element 5 and the inside bore wall of element 8. In other words, the bit 3, connector element 5, and the sleeve 6 all rotate as a unit until the desired alignment is attained. When the bit and connector element 5 are disconnected as a unit from the bowl stem 2, the sleeve 6 is retained within the stem 2 by the threaded member 8.

It will be understood that various modifications may be made in the form and arrangement of the elements constituting the embodiment illustrated in the drawings, without departing from the spirit of the invention.

Having described my invention, what I claim and desire to secure by Letters Patent is as follows:

1. A smoker's pipe comprising a bowl, a bowl stem, a bit; a first cylindrical connector element comprising a threaded insertable portion terminating at a shoulder and a cylindrical portion having a smooth portion and a knurled head, said head having a diameter slightly greater than that of a chamber located in said bit whereby heating of the bit effects expansion of the chamber walls allowing insertion of the knurled head portion to effect a permanently immovable grip; a second cylindrical connector element of expandable material, having an internally threaded bore and adapted to be inserted in a chamber located in said stem and adapted to fric-

tionally engage the wall of said stem chamber, and an externally threaded intermediate third cylindrical connector element having a smooth bore and a flange and adapted to be screwed into the bowl stem; said first connector element being inserted through the third connector element, with its smooth cylindrical portion engaging the smooth bore wall of the said third connector element and into the internally threaded bore of said second connector element; said second connector element being disposed in screw threaded relationship to the screw threads of said first connector element, said second connector element being retained within the stem by said third connector element when the bit and the first connector element are disconnected from the bowl stem, whereby a turnable tight fit between said bowl stem and bit is obtained.

2. The smoker's pipe of claim 1 wherein the
20 second connector element is of hard rubber.

JEROME GEVIRMAN.
